STAPLING MECHANISM FOR ROTARY
PRINTING MACHINES

Adolph M. Zuckerman, New York, N. Y., assignor
to R. Hoe & Co., Inc., New York, N. Y., a corporation of New York

Application June 24, 1942, Serial No. 448,282

9 Claims. (Cl. 1—7)

This invention relates to stapling mechanism for rotary printing machines, and more particularly to improvements to the class of stapling mechanism in which the staple inserting means travels in the direction of travel of the material to be stapled, and moves to the staple inserting point in the operation of carrying the staple into predetermined position relative to the material for its insertion therein, the staple carrying means coacting with a clinching device on a co-operating cylinder in setting the staples in associated sheets of the material, to thus produce a bound book-like product without interrupting the speed of travel of the material from which the product is formed.

In stapling mechanism of this type heretofore employed, a plurality of wire feeders or feeding heads are arranged in alignment longitudinally or axially of the stapling cylinder. A predetermined length of wire is fed to the staple forming means from each feeding head, and the staple is then formed and conveyed circumferentially of the stapling cylinder along an arcuate staple guide or horn to the staple setting point. This necessitates the staples being placed a distance apart longitudinally of the stapling cylinder, that is frequently in excess of the distance permitted by space available when stapling small products.

An object of this invention is to provide in a wire stapling mechanism for rotary printing machines an improved construction and arrangement which will permit the insertion of staples in traveling products relatively close together longitudinally of the stapling cylinder, so that a plurality of staples may be placed in a relatively small product.

Another object of this invention is to provide an improved stapling mechanism for rotary printing machines in which the staples are fixed in associated products between a pair of cooperating cylinders, one of the cylinders and its operable components being arranged to receive staple forming wire from a plurality of wire feeding heads positioned in cooperable relation with the cylinder and its staple forming components; the wire feeding heads and their driving mechanism being arranged for such disposition with relation to the cylinder as to permit staples to be inserted into the materials of the products at relatively short distances apart axially or longitudinally of the cooperating cylinders.

A further object of this invention is to provide for use in rotary printing machines an improved wire stapling mechanism having coop-

erating stapling cylinders and other parts which incorporate improved wire feeding drive instrumentalities which are constructed and arranged to so cooperate with the wire feeding mechanism of the wire feeding heads as to permit the wire feeding heads to be located relatively short distances apart longitudinally or axially of the stapling cylinders.

It is also an object of this invention to provide for use in a rotary printing machine a stapling mechanism of generally improved construction and arrangement, whereby the device will be simple, durable, and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion and minor details of construction may be made within the scope of the claims without departing from the spirit or sacrificing any advantages of the invention.

For a complete disclosure of the invention, a detailed description thereof will now be given in connection with the accompanying drawings forming a part of the specification, wherein:

30 Figure 1 is a diagrammatic elevation of a magazine press folder, showing the improved stapling mechanism applied thereto, the supporting frame of the folder being omitted;

Figure 2 is a fragmental elevation depicting 35 the cooperable stapling and clinching or die cylinders, the wire feeding mechanism and drive therefor;

Figure 3 is a developed or schematic view 40 taken partly around the stapling cylinder, seen in the direction indicated by the arrow 3, in Figure 2;

Figure 4 is a fragmental elevation of the 45 stapling cylinder and cooperating staple forming components;

Figure 5 is an enlarged view of a portion of Figure 2 showing the staple forming mechanism as seen on the line 5—5 of Figure 6;

Figure 6 is an enlarged view of a wire feeding head as seen in the direction of arrow 6 on Figure 5; and

Figure 7 is a fragmentary sectional view, as seen on the line 7—7 of Figure 5.

Referring to the drawings, in which similar reference characters designate corresponding parts, there is depicted a magazine press folder

(Figure 1) which includes a cutting cylinder 18 that supports a plurality of conventional cutting knives 11 which project radially from its peripheral portion. These knives cooperate with conventional cutting abutments or blocks 12 carried around the periphery of a cooperating cutting and transfer cylinder 13 to cut the web or webs into sheets of the required length. In the arrangement depicted, three cutting positions are arranged around the cooperating cutting cylinders, so that during each revolution of these cylinders three cut-offs are produced, although it is understood that any other required number of cut-offs may be provided for.

The cutting and transfer cylinder 13 is provided with conventional rockable impaling pins 15 which convey the cut sheets around the cutting and transfer cylinder to a collecting, folding and staple clinching cylinder 16. The collecting cylinder 16 is provided with three sets of conventional rockable impaling pins 17, which receive the sheets from the pins 15 and convey them around the cylinder 16 and deliver them to a jaw cylinder 18. In the preferred operation of the machine, the collecting cylinder 16 collects four cut-offs before delivering the sheets to the jaw cylinder 18.

A stapling cylinder 19 is operably supported by a rotatable shaft 20, and this cylinder is positioned for cooperable engagement with the collecting cylinder 16 at a point operably prior to the engagement of the collecting cylinder 16 with the jaw cylinder 18, in order to staple the associated sheets before they reach the jaw cylinder. The stapling cylinder 19 and its cooperating staple forming and setting components are of the type disclosed in the United States Patent Number 2,026,135, granted December 31, 1935, on application of Joseph E. Meyer, but the stapling arrangement herein disclosed, incorporates improved construction and arrangement over that shown in the Meyer patent, and provides means for placing staples relatively close together in a product, as will be more fully explained herein-after.

As shown in Figures 1, 2 and 3, wire feeding heads 21 and 21' are arranged in circumferentially spaced relation around the stapling cylinder 19 and in spaced relation longitudinally of the cylinder. As herein shown in Figure 3, the wire feeding heads are arranged in three rows. Those in the lowermost row, are located nearest to the longitudinal center of the stapling cylinder, the wire feeding heads in the intermediate row are located longitudinally outside of the lowermost heads, and the wire feeding heads in the upper row are located longitudinally outside of the intermediate wire feeding heads. By this arrangement the wire feeding heads and components of their drives are offset, and a wire feeding head in one circumferential row overlaps longitudinally of the cylinder, the adjacent circumferentially spaced wire feeding head.

The wire feeding heads that have driving sprockets 30 on the right hand side of their worm gears 27 are right hand feeding heads and are indicated by numeral 21, while the wire feeding heads that have driving sprockets at the left hand side of their worm gears 27 are left hand wire feeding heads and are indicated by numeral 21'. In the preferred arrangement shown no wire feeding head is adjacent and in longitudinal alignment with another head of the same hand, and staples may simultaneously be placed much closer together in a row longitudinally of the cylinder, than when like wire feeding heads are in longitudinal alignment. Although the arrangement as herein shown provides for three rows each having two wire feeding heads, it will be understood that a different number of rows of wire feeding heads may be disposed circumferentially around the stapling cylinder and a different number of wire feeding heads may be provided in each row.

The wire feeding heads 21-21' are supported by a bracket or sub-frame 22 secured to a brace member 23 carried by the machine frame.

Each wire feeding head is provided with a wire feed device having a feed shaft 25 provided with a worm wheel 26 which meshes with a worm 27 rotatably supported on a shaft or stud 28, and each worm 27 has a sprocket 30 which rotates therewith. Each sprocket 30 of the lowermost row of wire feeding heads, as viewed in Figures 1 and 2, is driven preferably by a chain 31, from a sprocket 32 carried by a common drive shaft 33 (Figures 2 and 3), which is rotatable in bearings 35 formed in or supported by the brackets 22. The sprockets 30 of the intermediate row of wire feeding heads 21 are driven by chains 36 from drive sprockets 37 carried by the drive shaft 33, and the sprockets 30 of the uppermost row of wire feeding heads 21 are driven through chains 38, which are trained around drive sprockets 39 carried by the drive shaft 33.

The drive shaft 33 has a gear 40 secured thereto adjacent one terminal, which gear meshes with an idler gear 41 (Figure 2) that is driven by a gear 42 carried by the stapling cylinder shaft 20, so that the shaft 33 is continuously driven in timed relation to the operation of the stapling cylinder 19, and will feed the correct length of wire required for a staple, during the length of time between successive stapling operations.

Wires W¹ are fed to the lowermost row of wire feeding heads 21-21' (Figure 2) from wire spools 45 and around pulleys or guide wheels 46. Wires W² are fed to the intermediate row of wire feeding heads 21-21' from wire spools 47, and wires W³ are fed to the uppermost row of wire feeding heads 21-21' from wire spools 48.

Each wire spool is rotatably supported on pins or studs 50 carried at the outer terminals of side members 51, forming a part of a spool holder. Each spool holder is provided with a split hub 52 that is clamped to a shaft or rod 53 which is supported by suitable members (not shown) that extend from the brace 23. Each split hub is clamped to the rod or shaft 53 by a clamp screw 55, so that each spool holder may be located in any desired longitudinal position along the shaft 53 for alignment with a wire feeding head.

As shown in Figure 6 each wire feeding head 21-21' is provided with a block 125 having a wire feed groove 126 and a pair of feed rollers, the first of which is shown and indicated by numeral 129, these rollers being positioned in alignment with the feed groove 126 to receive a wire W between them. The roller 129 is secured to a gear 131 and is rotatably supported on a stud 130. A gear 131 meshes with a similar gear (not shown) that is secured to the shaft 25, which is behind the stud 130 as seen in Figure 6. The second feeding roller is secured to the shaft 25, and thus when the worm wheel 26 is driven, the wire feed rollers are rotated to feed the wire to and through a groove or notch 177 in the wire guide finger 56, as shown in Figure 5. The finger 56 is pivoted on a pin 179 secured to a bracket 181 supported from the frame, and is biased by a spring 178'. The finger

56 is adjustable by means of a screw 182, which may be locked after adjustment by a nut 183.

The stapling cylinder 19, as shown in Figures 1 and 4 supports a rock shaft 57 having crank arms or levers 58 extending radially therefrom, and a cam roller 60 is rotatably supported at the outer terminal of the crank arm and is operably received in a cam groove 61 formed in a stationary cam. The rock shaft 57 has plunger operating members or levers 63 secured thereto, and each lever 63 is pivotally secured to a stapling plunger 65.

As shown in Figures 5 and 7 each stapling plunger 65 is formed with a body portion having right and left hand facing projections 158 and 158', each projection having a shoulder or cam surface 159 that may coact with a wire cutting arm 150, pivotally secured to a wire feeding head 21-21' by means of a shouldered bolt 151. These shoulders 159 are provided on both of the projections 158 and 158' in order that any stapling plunger may be used with either a right hand or a left hand wire feeding head.

The arm 150 is biased into engagement with an adjusting bolt 152 by means of a spring pressed pin 153. When a cam engaging surface 154 on the arm 150 is engaged by a shoulder 159, the arm 150 which terminates in a shear blade 155, is moved and cuts off a piece of wire, preparatory to forming a staple thereof as hereinafter described.

A grooved wire rest 160 (best shown in Figures 5 and 7), is provided for the purpose of supporting the severed staple wire and is arranged in the cylinder 19 between the opposed facing projections 158 and 158' on the plunger 65, which projections are formed with shoulders 161 to engage a length of wire preparatory to forming it into a staple. A hardened liner or horn guide 162 of a horn 66, is accommodated between the facing projections 158 and 158', the said liner having grooves on both sides as at 164 and 165. The horn 66, which is secured by screws 166 to any suitable portion of the brace 23 of the stapling machine has plates 167 and 168 fastened to the sides thereof, to which tip forming members or fingers 169, 171 are secured by bolts and nuts 172 and 173 respectively and act to slightly bend the ends of a formed staple inwardly, to facilitate clinching. Each of the tip forming members 169 and 171 has an inturned flange or cam surface 174 which is received in one of the adjacent grooves 164 and 165, mentioned above, wherein the opposite ends 175 and 176 of a length of wire, are thrust, and are bent inwardly by the said flanges 174, as the stapling cylinder 19 carrying the plunger 65 rotates in the direction indicated in Figure 5.

The stapling cylinder 19 coacts with the adjacent collecting and clinching cylinder 16 for the purpose of clinching the staples inserted in the sheets or products. The operation of cutting, forming and setting the staples may be summarized as follows:

When the stapling cylinder 19 and the collecting and clinching cylinder 16 are rotated in the direction indicated by the arrows, each plunger 65 moves outward and its cam surfaces 159 engage a cam engaging surface 154 and a knife arm 150 is moved to cause the shear blade 155 to cut off a length of wire that has previously been fed from a wire feeding head 21-21'. As the facing projections 158-158' of the adjacent plunger 65 sweep past the pivoted finger 56, the shoulders 161 pick up the piece of wire that has just been cut and is lying in the groove 177 of the finger 56.

Further movement of the cylinder 19 will cause an inclined face 184 of the horn guide 162, to press the center portion of the staple wire inward between the facing projections 158 and 158', thus forming the staple, and still further movement of the cylinder will bring the formed staple into engagement with the cam surfaces 174 of the tip forming fingers 169 and 171. As a plunger 65 passes the fingers 169 and 171, the cam 61 acting on the roller 60, causes the plunger to recede slightly so the ends of the staple project beyond the plunger and engage the cam surface 174, bending the tips of the staple as hereinbefore described.

After the plunger 65 has passed beyond the tip forming fingers 169 and 171, it is again projected and guides the wire as it engages the sheets on the clinching cylinder 16. After the staple meets the sheets, the plunger is gradually withdrawn and the staple is pushed through them by the grooved wire rest 160. The ends of the staple, being thus forced against the clinching cylinder, are bent over and clinched as they pass the bite of the cylinders 16 and 19.

After the clinching is effected, further rotation of the cylinder 19 again projects the plunger 65 in preparation for another cycle of operation.

After the staples have been set in the associated sheets, these sheets are carried further around the folding cylinder 16, and then the intermediate portions of the associated sheets are tucked between conventional fixed and rockable jaws 70 and 71 carried on the jaw cylinder 18 by conventional radially-movable tucking blades 72 carried by the collecting cylinder 16. The stapled and folded sheets after being gripped in the jaws 70 and 71 of the jaw cylinder 18 are then carried therearound and taken by grippers 76 on a delivery cylinder 17 which carries the products past spaced slitters 73 and 75 (Figure 1) which preferably slit the sheets into three products (Figure 3), and the products are then carried by the delivery cylinder until they are stripped from it by conventional stripper fingers 78 and deposited on a conveyer belt 80 which conveys the folded and stapled products or books to their destination. Although the provision of two slitters is the preferred arrangement, it is understood that a greater number of slitters may be employed if it is required by the nature of the product. If a greater number of slitters are provided to cut a greater number of products from each web or set of webs, then the disposition of the wire feeding heads and cooperating components lengthwise of the cooperating cylinders will accordingly be made.

The sprockets 32, 37 and 39 are each provided with a clutch jaw 85 (Figure 3) which is arranged to be engaged by a clutch member 86, mounted on the shaft 33, and each clutch member 86 may be locked into or from engagement with a clutch jaw 85 by a set screw 87 or other suitable securing device.

When it is desired to render one or more of the wire feeding heads inoperative this is readily done by merely moving one or more of the clutch members 86 from clutching engagement with the clutch jaws 85 of the selected sprocket or sprockets. By this arrangement, any number of wire feeding heads may be employed to meet the requirements of the product to be produced.

By offsetting the wire feeding heads in their positional relation around the stapling cylinder, they and their drive and feed components may be located so that a relatively great number of

staples may be inserted in relatively small products without using a plurality of stapling cylinders.

It will be understood that the invention may be embodied in other specific forms without departing from the spirit or essential attributes thereof, and it is therefore desired that the present embodiment be considered in all respects as illustrative and not restrictive.

Having thus described my invention, what I now claim as new and useful is:

1. A wire stapling mechanism including, a rotatable stapling cylinder, a cooperating clinching cylinder around which associated sheets of material are run and between the cooperating cylinders at their bite, a plurality of staple wire feeders positioned immediately adjacent the periphery of the stapling cylinder and in separate circumferential locations around the stapling cylinder with a wire feeder in one circumferential location overlapping longitudinally of the cylinder the adjacent circumferentially spaced wire feeder, means for severing pieces from the wire of each wire feeder, forming the severed pieces of wire into staples and conveying the staples circumferentially around the stapling cylinder to the bite line between the cooperating cylinders and there simultaneously setting the staples in alignment into the material.

2. A wire stapling mechanism including, a rotatable stapling cylinder, a cooperating clinching cylinder around which associated sheets of material are run and between the cooperating cylinders at their bite, a plurality of wire feeders positioned in axially aligned rows immediately adjacent the periphery of the stapling cylinder and each row being positioned in a separate circumferential location around the stapling cylinder with a wire feeder in one circumferential location overlapping longitudinally of the cylinder the adjacent circumferentially spaced wire feeder, means for severing pieces from the wire of each wire feeder, forming the severed pieces of wire into staples and conveying the staples circumferentially around the stapling cylinder to the bite line between the cooperating cylinders and there simultaneously setting the staples in alignment into the material.

3. A wire stapling mechanism including, a rotatable stapling cylinder, a cooperating clinching cylinder around which associated sheets of material are run and between the cooperating cylinders at their bite, a plurality of staple wire feeders positioned immediately adjacent the periphery of the stapling cylinder and in separate circumferential locations around the stapling cylinder with a wire feeder in one circumferential location overlapping longitudinally of the cylinder the adjacent circumferentially spaced wire feeder, a driven shaft, means operably connecting the driven shaft with each wire feeder whereby the feeders are driven from the common driven shaft, means for severing pieces from the wire of each wire feeder, forming the severed pieces of wire into staples and conveying the staples circumferentially around the stapling cylinder to the bite line between the cooperating cylinders and there simultaneously setting the staples in alignment into the material.

4. A wire stapling mechanism including, a rotatable stapling cylinder, a cooperating clinching cylinder around which associated sheets of material are run and between the cooperating cylinders at their bite, a plurality of staple wire feeders positioned immediately adjacent the pe-

riphery of the stapling cylinder and in separate circumferential locations around the stapling cylinder with a wire feeder in one circumferential location overlapping longitudinally of the cylinder the adjacent circumferentially spaced wire feeder, a driven shaft, means operably connecting the common driven shaft with each wire feeder whereby the feeders are driven, means for selectively disconnecting the connecting means between the shaft and each wire feeder so that any selected number of feeders may be driven from the shaft, and means for severing pieces from the wire of each wire feeder, forming the severed pieces of wire into staples and conveying the staples circumferentially around the stapling cylinder to the bite line between the cooperating cylinders and there simultaneously setting the staples in alignment into the material.

5. A wire stapling mechanism including, a rotatable stapling cylinder, a cooperating clinching cylinder around which associated sheets of material are run and between the cooperating cylinders at their bite, a plurality of staple wire feeders positioned in axially aligned rows immediately adjacent the periphery of the stapling cylinder and each row being positioned in a separate circumferential location around the stapling cylinder with a wire feeder in one circumferential location overlapping longitudinally of the cylinder the adjacent circumferentially spaced wire feeder, a driven shaft, means operably connecting the driven shaft with each wire feeder whereby the feeders are driven from the shaft, means for selectively disconnecting the connecting means between the shaft and each wire feeder so that any selected number of feeders may be driven from the shaft, and means for severing pieces from the wire of each wire feeder, forming the severed pieces of wire into staples and conveying the staples circumferentially around the stapling cylinder to the bite line between the cooperating cylinders and there simultaneously setting the staples in alignment into the material.

6. In a rotary stapling mechanism, a stapling cylinder having a plurality of staple forming and driving members arranged to simultaneously drive a plurality of staples into a product in alignment longitudinally of the cylinder, wire supply mechanisms for each of said members spaced circumferentially about the cylinder with a wire supply mechanism in one circumferential location overlapping longitudinally of the cylinder the adjacent circumferentially spaced wire supply mechanism so that they are positioned to supply staple wire to the said members successively.

7. In a rotary stapling mechanism, a clinching cylinder having a plurality of staple clinching members in alignment longitudinally of the cylinder along its periphery, a stapling cylinder having a plurality of staple forming and driving members similarly aligned to coact with the clinching members for simultaneously clinching staples driven into a product, a plurality of fixed wire supply mechanisms spaced circumferentially about the stapling cylinder with a wire supply mechanism in one circumferential location overlapping longitudinally of the cylinder the adjacent circumferentially spaced wire supply mechanism and each in position to supply wire to one of the said members.

8. In a rotary stapling mechanism, a stapling cylinder having a pair of staple forming and driving members arranged to simultaneously drive a pair of staples into a product, a wire supply mechanism to supply staple wire to each of the

said members, and means to support the said wire supply mechanisms in angularly spaced relation circumferentially about the cylinder with the wire supply mechanism in one circumferential location overlapping longitudinally of the cylinder the adjacent circumferentially spaced wire supply mechanism to supply wire to the said members successively as the cylinder rotates.

9. In a stapling mechanism, the combination with a rotatable stapling cylinder, a clinching device cooperating with the stapling cylinder to staple a product passing therebetween, and a plurality of staple forming and driving members carried by the stapling cylinder to simultaneously drive staples aligned in each passing product 15

transversely to the direction of its passing motion, of a staple wire supply mechanism for each of the said staple forming members and spaced circumferentially about the stapling cylinder with a wire supply mechanism in one circumferential location overlapping longitudinally of the cylinder the adjacent circumferentially-spaced wire supply mechanism, the circumferential location about the stapling cylinder of the wire supply mechanisms causing the wire to be supplied to the said staple forming members at different circumferential locations so that the staples are formed in sequence.

ADOLPH M. ZUCKERMAN.
